LOCK FOR ELECTRIC TERMINAL CONNECTIONS

Filed May 2, 1947

UNITED STATES PATENT OFFICE

2,511,906

LOCK FOR ELECTRIC TERMINAL CONNECTIONS

James W. Davis, Aberdeen, Wash.

Application May 2, 1947, Serial No. 745,416

1 Claim. (Cl. 287—111)

1

This invention relates to locks for electrical terminal connections, and the primary object of the invention is to hold electric terminal connections together, as for instance in extension cords where male and female plugs are joined together and where male plugs are inserted in wall sockets and the like.

One of the objects of my invention is to provide an electric terminal lock that is independently formed at terminal fittings so that these locks can be applied to any standard electric terminal fitting.

A further object of my invention is the provision of attachments for applying to wall plugs wherein the lock may be applied to said attachments and to the plug-in terminal of an electric cord.

These and other incidental objects will be apparent in the specification, drawings and claim.

Referring to the drawings:

Figure 1 shows the conventional electrical terminals, male and female, having my new and improved locking device mounted thereon, parts broken away for convenience of illustration.

Figure 2 is an end view of the terminal assembly taken on line 2—2 of Figure 1, showing my new and improved electrical terminal lock mounted thereon.

Figure 3 is a sectional view of the terminal and lock taken on line 3—3 of Figure 1.

Figure 4 is a perspective view of one of the parts or halves comprising my new and improved electrical terminal lock.

Figure 5 illustrates my method of attaching my new and improved terminal lock to a wall plug.

Figure 7 is a front view of the wall plug illustrating special fittings secured thereto and adapting my terminal lock thereon.

Figure 6 illustrates my terminal lock adapted to hold a screw-in plug to a male terminal and an electric light cord partially broken away for convenience of illustration.

Figure 8 is a detail section on the line 8—8 of Figure 2.

In the drawings:

I have illustrated standard electrical terminal connections, as for instance the male terminal 1 and the female terminal 2 attached to electric conducting wires 3 and 4. My preferred form of invention consists of the semi-cylindrical body 5. This body has a partial end closure 6 on both of its ends. A slit 7 is formed partially around the end closure permitting a flexibility of the body portion at 8. A groove 9 is formed longitudinal of said body portion on one side of the body 5 and a tongue 10 is formed on the opposite side.

An offset socket 11 is formed on each of the ends 6 and is adapted to receive the offset tongue 12 of the oppositely disposed body 5. The offset socket 11 and the tongue 12 prevents end movement of the two oppositely disposed body members 5, while the tongue 10 cooperates with the grooves 9 holding the two members tightly to-

gether when they are forced towards one another as best illustrated in Figures 2 and 3.

In the operation of the above described lock for electric terminals, the terminals 1 and 2 are joined together, then my lock consisting of two body members 5 are brought over the terminals and squeezed together, the tongues 10 springing into the grooves 9 and the tongues 12 registering with the sockets 11. The tongues 12 not only prevent end movement, but they provide a stop against which the inner walls of the members 5 contact preventing an offset movement of the members due to the pressure of the tongues within the grooves.

Figure 5 illustrates a modified application of my new and improved lock wherein hook members 13 are secured to a wall fixture 14 underneath the usual screws 15. The internal flange 16 of the members 5 register with the hook ends 17 of the members 13 while the end 6 engages the terminal plug 18. This provides a locking means for holding the electrical terminal 18 within the wall plug fitting 14.

Figure 6 shows another slight modification of my invention wherein a special flange 19 engages the outwardly extending flange 20 of the plug 21. The end members 6 engage the terminal plug 22 holding the said plugs together.

What I claim is:

30 A lock for electrical terminals, comprising two semi-cylindrical bodies for forming a cylindrical frame for embracing a pair of coupled terminal members, each of said semi-cylindrical bodies having in-turned end flanges and a resilient tongue formed along one of its edges and a locking element along the opposite edge, the respective resilient tongue and locking element on one element being on the opposite edges of the other semi-cylindrical body, each end flange of each of the semi-cylindrical bodies having a depression on one side and a lug on the opposite side, the lugs on one semi-cylindrical body fitting in the depressions on the opposite semi-cylindrical body, whereby when the two semi-cylindrical bodies are brought together the resilient tongues circumferentially lock the two bodies together and the lugs engaging the depressions prevent endwise movement of the bodies.

JAMES W. DAVIS.
